INVENTOR.

UNITED STATES PATENT OFFICE.

JAMES F. LANE, OF JACKSONVILLE, FLORIDA, ASSIGNOR TO GREENLEAF AND CROSBY COMPANY, A CORPORATION OF FLORIDA.

DESIGN FOR A BELT-BUCKLE OR SIMILAR ARTICLE.

SPECIFICATION forming part of Design No. 35,355, dated December 3, 1901.

Application filed September 30, 1901. Serial No. 77,149. Term of patent 7 years.

To all whom it may concern:

Be it known that I, JAMES F. LANE, a citizen of the United States, residing at Jacksonville, in the State of Florida, have invented and produced a certain new and original Design for a Belt-Buckle or Similar Article, of which the following is a specification, reference being had therein to the accompanying drawings.

Figure 1 is a front elevation of a belt-buckle embodying my design, and Fig. 2 an edge view of the same.

As shown in the drawings, the leading or material feature of my design consists in the arrangement of the representation of orange branches, leaves, and fruit.

In detail the outline of my design is formed by a sinuous branch A, showing a series of marginal swells a, b, c, and d, intermediate of which swells, respectively, are inwardly-

directed loops a', b', c', and d'. Near the terminal of the branch A, which forms part of the swell a, branch B sweeps inwardly, carrying a mass of intertwined leaves and tendrils and two oranges m and n, the former at the 25 right and the latter at the left of the center of the design.

It is apparent that my design is applicable to brooches and other similar articles.

Having thus described my invention, what 30 I claim as new, and desire to secure by Letters Patent, is—

The design for a belt-buckle or similar article, as herein shown and described.

In testimony whereof I have affixed my signature in presence of two witnesses.

JAMES F. LANE.

Witnesses:

S. D. HUNGERFORD,
M. A. BISHOP.
